REFRIGERATOR

Filed Sept. 6, 1927

UNITED STATES PATENT OFFICE.

HARRY E. KEENER, OF DENVER, COLORADO.

REFRIGERATOR.

Application filed September 6, 1927. Serial No. 217,802.

This invention relates to refrigerators and more particularly to the small refrigerators or ice boxes commonly used in homes for the preservation of food.

5 It is an object of the present invention to provide in a refrigerator of the above described character, a simple appliance for freezing water or other liquids and mixtures used in the production of ice creams, sherbets 60 and the like.

A further object is to provide means for accomplishing the aforesaid results without the use of electrical or mechanical devices and merely by the congealing influence of the ice, 15 ice and salt, or other refrigerant used for the preservation of the articles of food kept in the refrigerator.

Other objects of the invention are to be found in details of construction and a novel 20 arrangement of parts as will be disclosed in the course of the following description.

An embodiment of the invention has been shown in the accompanying drawings in which like characters of reference designate 25 corresponding parts throughout the views and in which

Figure 1 represents a perspective view of a refrigerator made in accordance with my invention,

30 Figure 2, a fragmentary and enlarged vertical section in the plane indicated by the lines 2-2 in Figure 3.

Figure 3, an enlarged and vertical fragmentary section taken on the lines 3-3 in 35 Figure 1.

Figure 4, a horizontal section along the line 4-4 in Figure 3;

Figure 5, a further enlarged sectional elevation of one of the freezing units of the 40 element as it is shown in Figure 3, and

Figure 6, a side elevation of the freezing element removed from the refrigerator.

The refrigerator or ice box 5 shown in Figure 1, comprises a food chamber 6 and an ice chamber 7 separated from each other by a vertical partition 8. The walls of the refrigerator are as usual made of suitable insulating structures and the ice chamber is lined with metal as indicated at 9.

50 Access to the food chamber is had by means of a door 10 in the front of the refrigerator and the refrigerant used for cooling the food, is placed in the ice chamber through an opening in the top of the refrigerator closed by a 55 lid 12.

My invention consists, briefly, in placing inside the ice compartment, one or more receptacles adapted to contain water or other liquids, or mixtures used in making ices, sherbets and the like. The receptacle or receptacles are so placed that they are fully subjected to the cooling influence of the refrigerant with which the ice compartment is filled, and the receptacles are arranged with reference to a door in the front of the refrigerator 60 so that they may be separately removed or replaced when the door is opened.

The method of supporting the receptacles as illustrated in the drawings is preferred by reason of its simplicity and practicability, 70 but it is to be understood that variations in the construction of the supporting means and the arrangement of the receptacles may be made without departing from the spirit of the invention.

75 The receptacles are provided in the form of trays 13 provided at their front end with handles 14 to facilitate their removal and replacement. Each tray is slidably supported in an individual box 15, the open front end of which is normally closed by the front end of the respective tray.

80 Grids 16 made of metal strips intersecting one another at right angles, may be loosely placed in the trays to divide the frozen contents thereof into small cubes or blocks which can be separately removed. The boxes and their respective trays, with or without the grids, constitute the freezing units and it will be readily apparent that any desired number 85 of these units may be used within the capacity of the ice chamber.

The various units in superposed relation to each other, are suspended in the ice chamber by means of a skeleton frame 17 which is fastened to the side walls of the compartment and which is provided with a hollow dome-shaped roof 18 to protect the freezing units from the falling ice while the chamber is being filled. The units are preferably spaced from each other to provide brine-passages 22 between them.

An opening 20 in the front of the chamber corresponding in size to the freezing appliance, is normally closed by a door 19 of insulating structure. It will be seen that when this door is opened all of the units are accessible for the removal or replacement of their trays so that the trays may be separately filled with the liquid substances to be frozen or

their frozen contents removed for use whenever desired.

The grids divide the ice in the trays into blocks or cubes which may be separately removed. The refrigerant used in the ice chamber preferably consists of a mixture of cracked ice and salt as indicated by the reference numeral 21, and owing to the arrangement of the freezing appliance in the ice chamber as hereinabove described, the units thereof are on all sides except that facing the opening in the front of the refrigerator subjected to the cooling influence of the refrigerant.

15 The trays are spaced from the top-, side-, and rear-end-walls of the respective boxes to provide for air spaces which aid in congeal-

ing the contents of the trays and in keeping them in a frozen condition.

Having thus described my invention, what 20 I claim and desire to secure by Letters Patent is:—

I claim:

In a refrigerator having an ice-chamber, a freezing element in the chamber in spaced 25 relation to the walls thereof, comprising a skeleton frame, including a hollow roof-member, boxes in the frame, sliding trays in the boxes, and a door in a wall of the refrigerator, affording access to the boxes. 30

In testimony whereof I have affixed my signature.

HARRY E. KEENER
